UNITED STATES PATENT OFFICE.

FRANK J. TRAFTON, OF JEFFERSON, IOWA.

SLOP-JAR ATTACHMENT.

1,173,468.

Specification of Letters Patent. Patented Feb. 29, 1916.

Application filed August 18, 1914. Serial No. 857,402.

To all whom it may concern:

Be it known that I, FRANK J. TRAFTON, citizen of the United States, residing at Jefferson, in the county of Greene and State of Iowa, have invented certain new and useful Improvements in Slop-Jar Attachments, of which the following is a specification.

This invention relates to improvements in receptacles, more particularly to receptacles employed as slop jars, waste jars in doctors' offices, garbage cans and the like, and has for one of its objects to provide a simply constructed receiver of flexible material adapted to be inserted within a rigid supporting body to receive the material and removable from the rigid body, to prevent the material deposited in the receiver from coming in contact with the supporting body.

Another object of the invention is to provide a device of this character having a member for supporting the receiver and removable together with the receiver.

With these and other objects in view the invention consists in certain novel features of construction as hereinafter shown and described and then specifically pointed out in the claims, and in the drawings illustrative of the preferred embodiment of the invention. Figure 1 is a perspective view of one of the improved devices in its preferred form; Fig. 2 is a vertical section of the device as illustrated in Fig. 1; Fig. 3 is a sectional view of a conventional bed pan with the improved device applied.

The improved device includes an outer rigid supporting body 10 which may be of any suitable material and of any suitable form and adapted to the purposes for which the device is to be employed, the improved attachment not being dependent upon the form of the supporting body. The supporting body will preferably be of porcelain or porcelain lined metal or the like, or of galvanized metal of the ordinary construction.

The improved attachment comprises a receiver 11 for the material which is formed of flexible material such as paper or the like and preferably water proofed. A supporting member 12 for the receiver forms a part of the invention and is preferably formed of foraminous material such as wire netting and conforming in outline to the outer body

and engaging within the same, and thus supporting the receiver. At its outer end the supporting member is preferably formed with an outwardly directed flange or rim 13 which bears over the outturned rim of the body 10 and is supported thereby. The supporting member is likewise preferably provided with lifting handles 14 to facilitate the handling of the supporting member and the receiver contained therein.

The handles 14 depending externally of the rim of the body 10 assist in supporting the member 12 in position. A cover 15 may be employed upon the device if preferred.

The improved device may be employed as a slop jar, a garbage can, or the like, and it is not desired, therefore, to limit the invention in any manner as to the form of the receptacle or the uses for which it is to be employed.

The improved device may likewise be applied to a conventional bed pan as illustrated in Fig. 3.

In employing the improved device, after the material has been deposited within the receiver, the supporting member together with the receiver may be removed from the supporting body, and overturned and the receiver and its contents discharged, the receiver thus being discarded and a fresh one applied to the supporting member. By this means the interior of the supporting body is protected from contamination from the material, as at no time does the material come in contact with the interior of the supporting body.

The receiver will preferably be constructed of paper as light as possible consistent with the strain to which it will be subjected, and may be discarded with its contents and a fresh receiver deposited within the supporting body.

Having thus described the invention what is claimed as new is:—

1. A device of the class described comprising a rigid body, a supporting member of foraminous material fitting within the rigid body and having handles extending above and depending externally of the rigid body, and a receiver of flexible material within said supporting member and removable therewith from the rigid body.

2. In a device of the class described, a rigid outer body having an outturned rim, a body of foraminous material within the outer body and having an outturned rim
5 engaging over the outturned rim of the rigid body, combined lifting and holding members swinging from the rim of said foraminous body and engaging over the rim of the outer rigid body, and a receptacle of flexible

material engaging within the foraminous body.

In testimony whereof I affix my signature in presence of two witnesses.

FRANK J. TRAFTON. [L.S.]
